TOOL BIT AND HOLDER THEREFOR

Ole Severson, Shelton, Conn., assignor to The
Apex Tool & Cutter Company, Inc., a corpora-
tion of Connecticut

Application October 10, 1933, Serial No. 692,916

1 Claim. (Cl. 29—100)

The invention relates to tool holders and tool bits, particularly designed for the metal working industries and for use in machines such as lathes, planers and the like.

5 It is among the general objects of the invention to provide simplicity and efficiency in a bit and holder assembly, so as to preclude movement of the bit with respect to the holder and the consequent chattering and inferiority in the finish of 10 the surface produced by the action of the bit upon the work.

Another object is to provide an assembly having maximum strength, so as to avoid the likelihood of fracture of the bit or holder, and, incident to this object, is the provision of a holder assembly which provides a large mass of bit material between the holder proper and its locking member.

Another object is to provide an assembly, the 20 locking member of which is adapted to force the bit rearwardly in firm contact with the holder body, thus, to provide large surface bearings for the bit and to insure its firm securement.

Other more specific objects and special features 25 of the invention will be apparent from a consideration of the drawing taken in connection with the accompanying description.

One special feature of the invention is the provision of a holder the forward end of which is 30 configured to co-operate with a cutting bit formed to co-operate therewith, and having a locking member which engages a front surface of the bit, so that, by adjustment, it will force the bit inwardly against the body of the holder, this being in contra-distinction to the more usual practice of forcing the bit outwardly against an abutment edge. The latter method, obviously, restricts the area of the abutment, whereas, in the 35 present structure, large bearing surfaces are provided so as to give an abundant embracement of the bit, and insuring both a strong and firm assembly.

In the drawing, Figure 1 is a side elevation of one form of the present invention.

45 Figure 2 is a similar view of another modification of the invention.

Figure 3 is a rear elevation of the bit of the assembly shown in Figure 1.

Figure 4 is a rear elevation of the bit shown in 50 the assembly in Figure 2.

Figure 5 is a side elevation of one form of locking element for the assembly; and

Figure 6 is an end elevation of the locking element shown in Figure 5.

55 In the forms of the invention shown in Figures

1 and 2, the body of the tool holder is identified by the numeral 10, a simple, elongated, rectangular body being illustrated. It will, of course, be understood that this particular form of body is used merely by way of simplified illustration. In the practical application of the assembly, various forms of bodies may be employed. In both forms of the invention here shown, the forward end of the holder is of configuration to receive a tool bit of co-operating design. The tool bit is identified by the numeral 11, and includes a suitably designed cutting tip 12, the shape or design of which is of no consequence to the present invention. In both instances, the holder includes a substantially longitudinal platform 13, over which a corresponding face 14 of the bit lies. The forward end of the platform 13 is terminated in both instances by a step 15, upon which a widened head, or seat, 16 of the locking bolt 17 rests.

The locking bolt 17 extends rearwardly through the body and longitudinally thereof, its opposite end being threaded and provided with a nut 18, which, by adjustment, will draw the bolt back, thus, moving the tool seat 16 back towards the body proper. The seat 16 engages the front face of a step 19 of the tool bit, thus, forcing it securely back, seating it against the co-operating faces of the body. Obviously, the structure and adjusting means for the bolt may be modified; a compound bolt may be employed, or a different adjusting means used. It is suggested that the seat 16 may be a separate, hardened steel element, thus, to add strength and rigidity to the assembly.

In that form of the invention shown in Figure 1, the platform 13 is met by an outwardly-inclined surface 20, against which the co-operating face 21 of the bit is forced by the action of the locking bolt. This arrangement provides a large mass of material between the tool seat and the holder body, thus, imparting maximum strength; the inclining of the surfaces also insures firm seating of the bit, insuring vibrationless securement thereof. In this form of the invention, a lock against transverse movement of the bit is provided by co-operating serrations on the surfaces 20 and 21. It will be noted that this, as well as the hereinafter described means for locking the bit against sidewise displacement, permits sidewise adjustment of the bit before locking, so as to permit different settings of the bit with respect to the longitudinal axis of the holder, thus, to compensate for wear of the bit.

In that form of the invention shown in Figures 2 and 4, the front of the holder is provided, ad-

jacent to the platform 13, with a pair of spaced, oppositely-inclined surfaces 22 and 23, which, in co-operating with faces 24 and 25, insure a proper three-surface seating of the bit, which not only insures its rigidity, but divides the strain of securing and of operating. This form of the invention not only accomplishes the object herein set forth, but, in addition, accomplishes the objects and advantages of the Lindmark Patent 10 #1,443,752.

To provide for transverse securement of the bit, this form of invention utilizes a Woodruff key 26, which is mounted in the bolt 17, or which may be formed in the holder body. The key engages slots 15 27 in the surface 14; by selecting the slot which is engaged by the key, the setting of the bit with respect to the longitudinal axis of the holder may be varied.

A further modification of the lock-restraining, 20 transverse movement of the bit is illustrated in Figures 5 and 6, in which the seat 16 is provided with a rib 28, formed directly thereon, and, in this instance, the slots, which are adapted to selectively receive it, are formed in the bit in that 25 portion directly overlying the seat.

In considering this phase of the invention, it will be noted that the various modifications of such locking means are equally interchangeable between the types of bits shown. It is also sug-

gested that transverse locking may be secured through the use of a locking screw covered by the upper overlying portion of the body, as in the manner of the screw of the Lindmark patent mentioned above. In general, it will be understood that the invention is not restricted to the specific structural details illustrated, and that numerous changes, modifications and the full use of equivalents may be resorted to without departing from the spirit or scope of the invention as 10 outlined in the appended claim. 5

What I claim is:

A tool holder including an elongated body cut away at one end to provide a bit-receiving platform and a tool seat platform; and a longitudinally-extending draw-bolt, terminating in a tool seat extending forwardly of the bit-receiving platform and upon the tool seat platform; and being adapted to engage a tool bit, whereby tightening of the bolt will cause the seat to force a 20 tool bit rearwardly on the bit-receiving platform, said holder including an outwardly-inclined surface co-operating with the bit-receiving platform, and being adapted to receive the rear face of the bit, and to urge the bit downwardly towards the 25 bit-receiving platform, said surface being serrated to co-operate with a similar surface of a bit to restrain the same against transverse movement.

OLE SEVERSON.
